UNITED STATES PATENT OFFICE.

WILLIAM D. SNYDER, OF COLUMBIA CITY, INDIANA.

FOLDING BEDSTEAD.

SPECIFICATION forming part of Letters Patent No. 318,813, dated May 26, 1885.

Application filed February 16, 1884. (No model.)

To all whom it may concern:

Be it known that I, WILLIAM D. SNYDER, a resident of the town of Columbia City, in the county of Whitley, State of Indiana, have invented certain new and useful Improvements in Folding Bedsteads; and I do hereby declare that the following is a clear, full, and exact description of the invention, which will enable those skilled in the art to which it appertains to make and use the same, reference being had to the accompanying drawings, which form a part of this specification, and in which—

Figure 1 is a vertical sectional view of my improved bed when open. Fig. 2 is a similar view of the same closed. Fig. 3 is a similar view of the lower part of the bed, showing it half open or closed. Fig. 4 is a horizontal view of section on line *xx* in Fig. 1.

My invention relates to that class of folding beds using a shifting fulcrum or pivot, upon which the bed is folded, in connection with a panel sliding vertically in the back of the bed, to which a suitable counter-balance is attached; and it consists in the improved construction and combination of such parts.

In the drawings, *A* indicates the frame or casing, into which the bed-frame *B* is folded, and two horizontal ways, *C*, which are either smooth or cogged, are secured upon the inner sides of the side pieces of the casing, near their lower ends, the rockers *D*, which are secured upon the outer sides of the side pieces of the bed-frame, near their inner ends, rocking upon these ways and forming the traveling fulcrum.

A panel, *E*, is hinged at its lower edge to the upper edge of the head-board *F* of the bed-frame, and is hinged at its upper edge to the lower edge of a sliding panel, *G*, which is provided with grooved anti-friction rollers *H*, which engage with the two beaded guides or ways *I*, secured vertically upon the inner sides of the side pieces of the casing *A*, near their rear edges.

A counterpoise, *J*, is secured to the sliding panel *G*; and it will be seen that when the bed is folded up in the casing the swinging panel *E* will occupy a vertical position, causing the counterpoise to bear directly upon the upper edge of the head-board of the folding bed part,

thus holding it securely closed, and as the outer end of bed-frame is lowered the swinging panel will push the sliding panel upward, gradually swinging outward at its lower edge until the panel, when the bed is unfolded to its horizontal position, will bear against the bed in a downward and outward position, thus holding the bed-frame securely open, and preventing it from closing prematurely.

By the construction of the parts and their operation, as thus shown and described, the bed, when open, is thrown out of the casing to such an extent that the head of the occupant is not confined within the casing, thus insuring better ventilation and greater comfort than in the usual construction of such beds, wherein the head of the bed-frame is confined altogether within the casing.

By referring to the drawings it will be seen that in an open position, as in Fig. 1, the fulcrum is at the point *Z*, in Fig. 3 at the point *Y*, and in a closed position at *X*, as in Fig. 2. By this shifting of the fulcrum the weight of the counterpoise attached to the sliding panel and the weight of the bed-frame are equalized in any position, excepting the open and closed positions, as before stated, thereby greatly facilitating the opening or closing of the bed.

The legs or supports *K* for the outer end of the swinging bed-frame are preferably hinged so as to fold downward when the frame is raised, forming a crown-piece for the casing.

The grooved anti-friction rollers *H*, in connection with the vertical beaded guides *I*, form a guide for the sliding panel *G*, which prevents the panel from cramping or binding in its upward and downward motion incident to the vibrating of the bed-frame in opening or closing the bed, thereby avoiding any tendency to throw the bed over in opening it, and using all of the weight of the counterpoise, as none is lost by the friction, as in the ordinary method.

While I prefer the position of the horizontal ways *C* in Figs. 1, 2, and 3, I do not wish to limit myself to it, as the ways *C* may be set at an angle, the inner end lower than the outer end, without materially changing the working of the rockers upon them.

I am aware that folding beds have been made with shifting fulcrums of various kinds in connection with the sliding panel and counterpoise; but I am not aware of any construction in which the horizontal ways and rockers, as described in this specification, in connection with the swinging panel and the sliding panel, as described, have been used. These I regard as very desirable features in a folding bed, as it will be seen by referring to drawings that the bed is brought close to the floor in an open position, and it is easily closed by employing a minimum weight of counterpoise.

15 I am aware that the state of the art shows it to be old in folding bedsteads to construct a panel to slide in grooves in connection with anti-friction rollers and counterbalancing weights or springs, and to swing the bed with-
20 in the bed-frame upon shifting fulcrums, said fulcrums consisting of horizontal and curved bars or plates provided with cogs; and I do not therefore claim any of these features, broadly.

25 My claims are based upon a peculiar ar-
rangement and combination of previously-
known parts; but by my arrangement, especially of the jointed panels and rockers, when the bed is open the upper panel bears upon the lower one in a downward and outward
30 position, so as to hold the bed steady and obtain the advantage, already described, of throwing the head of the bed practically out of the casing, and by which arrangement of panels and rockers the bed is also prevented from
35 closing prematurely; also, by my arrangement of rockers the upper rocker can be ad-
justed so as to bring the bed closer to the floor, and still present the same leverage as in a higher one; and, finally, in reducing the fric-
40 tion and adding to the general convenience of operation by the arrangement of anti-friction rollers and the counterpoise.

Having thus described my invention, I claim and desire to secure by Letters Patent of the United States—

1. In a folding bed, in combination with the casing A and the frame B, the horizontal ways C, secured upon the inner sides of the side pieces of the casing, near their lower ends, the rockers D, forming the traveling fulcrum and 50 secured upon the outer sides of the side pieces of the bed-frame, near their inner ends, the head-board F, of the form shown, the sliding panel G, provided with grooved anti-friction rollers H, engaging with the beaded guides in 55 ways I, the panel E, hinged at its lower edge to the upper edge of the head-board F and at its upper edge to the lower edge of the sliding panel G, and the counterpoise J, secured to the back of the sliding panel G, substantially as 60 described.

2. In a folding bed, the sliding panel G, the counterpoise J, secured to the back of the panel G, the swinging panel E, and the head-board F, of the form shown, the said panel E 65 hinged at its upper end to G and its lower end to F, the horizontal ways, and the rockers, all arranged as shown, whereby when the bed is folded up the said counterpoise will bear directly upon the upper edge of the said head-board, and when the bed is lowered the sliding panel G is forced downward and outward against the head-board F, and the head-board F forced and held outward, so that the head of the bed shall be nearly outside of the casing, 70 substantially as described.

In testimony that I claim the foregoing as my own I have hereunto affixed my signature in the presence of two witnesses.

WM. D. SNYDER.
